ABSTRACT: A wire frame garbage bag holder for use with resiliently expandable garbage bags of synthetic resinous type. Means provided for maintaining the free upper edge of the bag in tensed relation, so that it does not slip with respect to the device under load.

GARBAGE BAG HOLDER

This invention relates generally to the field of garbage disposal devices, and more particularly to a resilient bag retaining stand capable of supporting a synthetic resinous bag in open-mouthed position for filling, and so constructed that the bag may be readily disengaged for subsequent disposal when required.

It is among the principal objects of the present invention to provide an improved low cost device which may be readily fabricated, to permit consequent wide sale, distribution and use throughout the purchasing public.

Another object of the invention lies in the provision of a garbage bag holder particularly adapted for use in conjunction with synthetic resinous garbage bags of a type most conveniently fabricated of a thin gauge resilient, nonporous synthetic resinous material, such as rubber hydrochloride, polyethylene and the like.

A further object of the invention lies in the provision of a device adapted to be used in conjunction with a stretchable garbage bag, the device incorporating resilient means for maintaining the bag in open-mouthed condition for loading, and for retaining the upper free edge of the bag in stressed condition to maintain itself upon the device, irrespective of the degree of loading of the bag.

Still another object of the invention lies in the provision of an improved garbage bag holder which may be selectively engaged and disengaged with a resilient garbage bag by those possessed of only ordinary strength and skills, and without the use of any tools.

A feature of the disclosed embodiment lies in the unusually attractive appearance of the same.

These objects and features, as well as other incidental ends and advantages, will more fully appear in the progress of the following disclosure, and be pointed out in the appended claims.

In the drawing, to which reference will be made in the specification, similar reference characters have been employed to designate corresponding parts throughout the several views:

FIG. 1 is a side elevational view of an embodiment of the invention.

FIG. 2 is a front elevational view thereof.

FIG. 3 is a top plan view thereof.

FIG. 4 is an enlarged fragmentary sectional view as seen from the plane 4-4 in FIG. 2.

In accordance with the invention, the device, generally indicated by reference character 10, is preferably of welded wire construction, and comprises broadly a lower frame element 11, a vertical support element 12 and an upper frame element 13. Positioned within the lower frame element 11 is a tray element 14 which is optional and selectively removable. A garbage bag 15, of resilient, nonporous synthetic resinous material selectively engages the upper frame element 13 and a part of the vertical support element 12.

The lower frame element 11, includes a first circular member 17, the lower surface of which is adapted to be supported by a floor or other horizontal supporting surface. A second or upper circular member 18 is of identical configuration, and is interconnected to the first member 17 by first, second and third vertical interconnecting members 19, 20 and 21, respectively, which are welded at interconnecting points 22 to maintain the members 17 and 18 in relatively parallel horizontal planes.

The vertical support element 12 includes first and second vertical support members 24 and 25, respectively, welded at points 26 to members 17 and 18 at the lower portion 27 thereof. The upper portions 28 of each of the members 24 and 25 are provided with a notch-forming member 29, including a lower angularly disposed portion 30, a vertical portion 31 and

an upper angularly disposed portion 32 which form an outwardly facing notch or recess 33.

The upper frame element 13 overlies the lower frame element 11, and includes a horizontally disposed arcuate portion 39 having first and second relatively resilient sections 40 and 41, respectively. The free ends 42 and 43 are resiliently biased with respect to each other, and include downwardly extending portions 44 and 45, respectively, each including a notch-forming member 46 and 47, respectively, which correspond in size and position to the notch-forming members 29 on each of the vertical members 24 and 25. Each notch-forming member includes upper and lower angularly disposed members 48 and 49, respectively, which are interconnected by a vertical member 50 to define a notch or recess 51. Extending downwardly from the notch-forming member are looped finger-engaging portions 52 which enable the free ends 42-43 to be moved toward each other by the fingers of one hand, as when engaging and disengaging a bag 15.

The tray element 114 is supported upon the upper member 18 of the lower frame element 11, to provide a support for the lower end of the bag 15. It includes a circular sidewall 55, a lower wall 56, and a flange 57 of diameter slightly larger than the member 18 to rest thereupon.

The bag 15 is installed upon the device 10 by passing the open-mouth formed by the upper edge 60 through the upper frame element 13, and spreading the edge to engage the notches or recesses 33. This action may be assisted by engaging the finger-engaging portions 52 and moving them toward each other, to slightly reduce the radius of the arcuate portion 39, and after engagement, the members 52 may be subsequently released whereby the resilient contraction of the upper edge 60 coacts with the resilient expansion of the arcuate portion 39. The bag 15 may be subsequently filled to capacity, weight exerted on the lower end of the bag tending to exert a stress on the bag side 59 tending to increase the purchase of the same upon the upper frame element 13, and preventing disengagement of the edge 60 from the notches 33 and 51.

When the bag has been completely filled, the finger-engaging portions 52 are again moved toward each other, to facilitate disengagement of the upper edge 60 from the notches, following which the bag mouth may be closed, and the bag disposed of. During this operation, the lower end of the bag is supported by the lower wall 56 of the tray element 14.

I wish it to be understood that I do not consider the invention limited to the precise details of structure shown and set forth in this specification, for obvious modifications will occur to those skilled in the art to which the invention pertains.

I claim:

1. Garbage bag holder construction comprising: a lower frame element having a lower surface adapted to contact a horizontal supporting surface, a vertically disposed support element attached at a lower end thereof to said lower frame element, and having notch-forming means adjacent to and below an upper edge thereof, an upper frame member of generally planar arcuate configuration attached to said upper end of said vertical support element and including a pair of resiliently biased sections defining a generally circular opening therebetween, the free ends of said sections having downwardly extending notch-forming means disposed generally opposite said first mentioned notch-forming means, said sections vertically overlying said lower frame element.

2. Structure in accordance with claim 1, including a disposable bag element of resilient, nonporous material having a generally cylindrical sidewall defining an upper edge, said edge being selectively positioned within said first and second notch-means.
